PARAFFIN TOOL

Edwin Hebert, Breaux Bridge, La., assignor to Southern Research and Sales Corporation, a corporation of Louisiana

Filed June 29, 1959, Ser. No. 823,549
9 Claims. (Cl. 166—172)

The present invention pertains to an apparatus for scraping, cutting, and removing sediments from the inner walls of a substantially vertical fluid conduit.

More particularly, the invention pertains to an apparatus for cleaning accumulations of paraffin from the casing of oil wells, and of sludge and bacterial growth from water, gas, sewer and other pipes.

To identify the apparatus further, it is suitable for insertion into substantially vertical pipelines, such as a well for actuation therein from above ground, and it employs cleaning means such as a knife, a scraping cutter, a brush, or combinations thereof mounted on a weighted central member for propagation of the cleaning means axially relative to the well casing.

In fluid conduits of the type described, sediments deposit on their inner walls, of varying consistencies and states of solidifications, usually not evenly throughout the line, but sporadically, occurring only at certain levels, for varying lengths, narrowing the bore of the conduit, and thus decreasing its output. The irregular distributions of the sediments contribute to the difficulties of cleaning the lines.

The devices of this type employed by prior art for cleaning oil wells by mechanical means, teach the lowering of a heavy tool into the well. The tool is suspended by means of a steel wire. Attached to the bottom end of the tool below a weighted portion thereof is a "knife," the purpose of which is to dislodge the paraffin, the cutting or scraping action of the "knife" resulting from the downward motion of the tool by gravity. When the paraffin is hard, or present in large quantity, and stops the descent of the tool, further descent is obtained by means of a hammering or jarring action of the tool. This action is accomplished by the operator pulling on the wire, thereby raising the weight, then releasing the wire, dropping the weight to thus strike out and restart the knife.

As the paraffin is cut away from the pipe it has to flow past the bulky weight. In so doing, it sticks to the tool and impedes the flow of oil past the tool. If this impediment to flow becomes great enough, the pressure of the oil below the tool may actually blow the tool up the well, causing a great deal of danger and also difficulty as a result of tangled wire. Since the paraffin is cut away from the pipe below the tool, the descent of the tool tends to push this dislodged paraffin ahead of it; thus impeding the progress of the tool. The rigid ring-shaped knives of the prior art, being inflexible, often get jammed in a pinched portion of the pipe. In addition, since the ring-knife is concentric with the pipe and in the same plane as the joints in the pipe, the knife may become lodged in the joints. Additional difficulties of the devices of the prior art are caused by their frequent dismemberment in the pipe line during the cleaning operation, during attempts to remove them by force when stuck. Every prior device known increases obstacles to the flow of the fluid during the cleaning process.

The primary object of the invention is to obviate these deficiencies of the prior art apparatus for scraping, cutting, brushing, and removing sediments from wells and similar fluid conduits.

Another object of the invention is to provide a device

2

of this kind which eliminates the downward pushing into the well of the scraped off sediments.

Another object of the invention is to position the weighted bulk of the tool below the cutting knife or other cleaning means.

Another object is to provide a tool, the bulk of which passes through the center portion of the undisturbed sediment and is followed by the knife to cut and disrupt the sediment.

Another object of the invention is to position the cutter so that the removed sediment flows away from the knife without impeding or being impeded by any part of the tool.

Another object of the invention is to cut and remove sediments and to facilitate the upward progress of the scraped off sediments to removal by utilizing the upward flow of the fluid itself for flushing the apparatus.

Another object of the invention is to provide a tool which utilizes the flow of the fluid to clean the knife during operation.

Another object of the invention is to provide a tool which permits a continuous and uninterrupted flow of fluid through it while in operation.

Another object is to provide a tool design which presents a minimum of obstructions to which paraffin or other sediments can adhere during passage through the conduit.

Another object of the invention is to provide a knife which presents a minimum obstruction to the free flow of sediment once removed.

Another object of the invention is to provide a knife which will require a minimum of repair and replacement per units of work accomplished.

Another object of the invention is to provide a knife which will not jam in pipe joints, pipe imperfections, or in hard sediments.

Another object of the invention is to provide a tool of minimum overall weight, light enough for convenient handling yet of highest efficiency.

Another object of the invention is to provide a combination suspension cutter and knife assembly which permits the positioning of the knife at the extreme upper end of the tool.

Another object of the invention is to provide a guide rod on which the cutting knife can be attached to a sleeve or collar.

Another object of the invention is to provide a tool having interchangeable component parts, so that tool makeup, weigh, diameter, and length can be easily adapted to the particular need.

Yet another object of the invention is to provide a tool of the kind described combining advantageously a central rod, weight, cutter, and suspension means in an assembly designed specifically for optimum cooperation and improved joint performance.

Other objects and many of the attendant advantages of this invention will be readily appreciated as they become better understood by reference to the following detailed description when considered in connection with the accompanying drawings, in which like reference numerals designate like or corresponding parts throughout the figures thereof, and wherein:

FIGURE 1 is a cross-sectional view through a well-casing, with a portion shown broken off, with portions of the apparatus of the invention shown therein in side view, diagrammatically and in cross-section;

FIGURE 2 is a similar view of another embodiment of the invention;

FIGURE 3 is a cross-sectional view of a complementary part of the bottom part of the device, common to the embodiments of FIGURES 1 and 2;

FIGURE 4A and 4B are views of cutters of the inven-

tion, common to the embodiments shown in FIGURES 1 and 2;

FIGURE 4C is a view of a brush which may be used alone or in assembly with the cleaning means of FIGURES 4 or 5;

FIGURES 5A and 5B are perspective views of another embodiment of a cutter which may be employed with the embodiments of FIGURES 1 or 2;

FIGURE 6 is a cross-sectional view of a detail of the apparatus of FIGURE 2;

FIGURE 7A is a view of a helically-shaped cutter integral with a vertical vane attached to a sleeve-type collar or tube section;

FIGURE 7B is a view of a helically-shaped knife integral with a vertical vane with two separate collars; and

FIGURE 8 is a cross-sectional view of a combination of the knife-guide rod and rope socket which are interchangeable with assemblies common to embodiments of FIGURES 1 and 2.

There is shown, in FIGURE 1, a vertical well casing 11, a knife-guide rod 12, suspended therein axially by means of wire or cable 13 by means such as a socket 14 with lock-nut 15, or as shown and described with reference to FIGURE 8, by forming a knife-guide rod 12 as a fishing head 18a centrally bored at 40 to accommodate wire or cable 13 which is secured below the base of said knife-guide rod by means such as the ring or eyelet 47.

The wire is fed from above the well manually or by motor means, not shown, preferably over a pulley from a rotatable drum 17. These are conventional means and form no part of the present invention.

The upper end of the rope socket is provided with a flange 18, permitting engagement with an auxiliary fishing tool, not shown, should the wire 13 fail. The diameter of the flange is of minimum safe dimensions, to provide ample space between it and the inner wall of the casing.

The central knife-guide rod 12, shown in FIGURE 1, is connected at its bottom end to an elongated weighted tube 19. The weighted tube, preferably made of lead, comprises an inner axial bore 20 with bypass orifices 21. The tube has a radius proportioned to the radius of the well casing and to the rate of flow of the fluid within the well, as will be hereinafter discussed.

The weight of the tube 19 is predetermined by the diameter and length of the tube and by the anticipated sediment and flow of fluid upward through the conduit. The outer surfaces of the tube 19 are smooth. The tube member 19 is provided at its head portion with means to fixedly engage the bottom part of the central rod, permitting axial suspension of the weighted tube within the casing. Conventional means are utilized for this purpose, such as threading of the members and securing by lock-nuts 23 and 24. In a simple form, the rod 12 is threaded at its bottom, is screwed into the weighted tube which is internally threaded, simultaneously closing the central axial bore 20 at its top and a lock nut 24 secures the connection. A circumferential groove 25, FIG. 6, is provided in the upper end of tube 19, below projection 23 for engagement with a fishing tool (not shown), should the rod 12 and the weighted section become separated. The diameter of the weighted tube is smaller than that of the casing as will be hereinafter discussed. The length of the weighted tube is predetermined by various factors of the entire assembly, such as its radius and weight.

The tube is tapered at its bottom end. In FIGURE 3, a tip 26 is shown axially bored at 27, threaded at its top at 28, having preferably a top diameter the same as and axially aligned with the bottom of the weighted tube 19. The tip is tapered as shown, and in accordance with the invention serves as the bottom end of the tube which has a corresponding thread 28 in its lower end.

FIGURE 4A shows a cutter-blade or knife 29, attached at its upper end to a sleeve 30 and at its other end to

collar 31 which is slidably mounted on central rod 12. The cutter-blade is shown as having a helical shape mounted axially over and extending about the central rod, the diameter of the helix being just slightly less than that of the casing.

In another embodiment of the invention, however, the cutter-blade is made of spring steel of a predetermined length and resiliency, related to the weight 19.

In FIGURE 4A, collar 31 is mounted on the central rod 12 in position adjustably fixed by a set screw 31a, while the upper collar 30 is movable. A stop may be provided by a set screw 30a fixed in rod 12. During cleaning operations, the lateral dimensions of the cutter-blade, that is, the effective radius of the helix formed thereby, will change automatically. In response to a considerable increase in the density or hardness of the sediment in the pipe an increased pressure will result on the cutter's edges. The top collar 30 of the cutter, when freely movable, will distance itself automatically from the bottom collar 31. The helix defined by the resilient blade will thus elongate its lateral diameter will decrease and the angle of its cutting edge relative to the wall will decrease. Thus, the cutter's radial sphere of cutting influence will be reduced to an adequate ratio and will increase automatically on reciprocation after a layer of the sediment has been sliced off, or after the deposit accumulation in the following stages of its progress decreases. By these means a definite variable optimum relationship between the distance of the cutter's top and bottom sleeves, and its natural slope are obtained relative to the radius of the pipe, limited only by the predetermined resiliency of the cutter blade. Since the complexity of the factors involved makes precalculations very difficult, the adjustability of the sliding means 30a and 31a, here described, permits easy and quick experimentation of the optimum positions of the collar 31 relative to the stop of the upper sleeve 30. Cutters of different resiliency may be easily and quickly substituted. In the spirit of the invention, the top sleeve 30 may be fixed to the central rod 12, with collar 31 fixed or slidably, depending on the particular requirement in the field, such as the degree of hardness of the deposit to be removed.

In another embodiment of the invention the cutter blade, instead of being a helically wound cutter blade, is a spiral cutter blade, FIGURES 5A and 5B, having a bottom turn of the same diameter as that of the weighted tube, the diameters of the subsequent turns increasing in sequence up to a maximum diameter almost equal to the diameter of the casing, may be employed with or without the differently sliding sleeve arrangement of the two collars described with reference to FIGURE 4A. The helical or spiral cutter blades of FIGURES 4A and 5A are provided preferably with conventional tapered knife edges on their upper and lower peripheries, as shown at 29a and 29b, in FIGURE 8.

While one full loop to the cutter bar is necessary, a plurality of loops, depending on the selected weight, velocity, and momentum factors, are desirable.

The axial bore through tube 19 with the branches or by-passes 21 at its head and with a circumferential spacing between the outer wall of the weighted tube and the inner wall of the casing, as shown in FIGURE 1, are calculated to provide for a flow of the fluid upwards through the well without interruption during the cleaning process. In fact, the cleaning process advantageously utilizes any such existing flow to transport the sediments, separated from the wall of the casing by the cutter blade, upwards and out of the well. To aid this function of the weighted tube, the diameters of the inner bore 20, of the branches or bypass orifices 21 thereof, and of the weighted section 19, are scaled carefully relative to the diameter of the casing and the expected thickness of sedimentation to produce a jet-type flow through and around the weighted tube upwards. The optimum weight of the weighted tube is related to the resiliency and to the scraping surface of the

cutter blade, to the expected amount of sedimentation on the wall of the casing, to the length of the tube, and to the velocity of impact. The means to control the resiliency and angle of cutting of the knife are shown as set screws 30a and 31a for purposes of illustration, and other means may be substituted without departure from the spirit and scope of the invention.

Again the complexity and uncertainty of the many factors involved make it often impractical to precalculate these dimensions. Therefore, in a preferred embodiment of the invention, such as shown in FIGURE 1, means are provided to vary the weight of the tube member 19. The tapered bottom tip, being easily removable, offers the opportunity of interposing additional tube sections 22, screwed to the bottom of the weighted tube as its continuations, prior to the attachment of the tapered bottom tip, to add extra weight if necessary. Such continuation sections also may have a diameter greater or smaller than that of the top weighted tube 19 to aid in the formation of an optimum jet flow through the axial bore by decreasing the spacing between casing and tube.

During the well cleaning operation the apparatus is lowered into the casing from drum 17, with the cutter-blade following the weighted tube by gravity. When the cutter-blade engages a sediment which it cannot slice off the wall by its own weight and momentum, the weighted tube continues its downward progress unimpeded, while the cutter-blade is still stuck or retarded in progress in the sediment. If the cutter arrangement includes the variable distancing of the two sleeves, as described above with reference to FIGURES 4A, 4B, 5A and 5B, the resiliency of the cutter-blade comes first into effect and may help the blade to complete the cutting of the sediment and free itself. If this does not suffice, or the arrangement has not been included, the socket 14 hits the upper sleeve of the cutter bar with the weight and momentum of the weighted tube, and a jarring impetus is imparted to the cutter blade sufficient to make it resume downward travel.

With the knife being located at the top end of the tool, all of the paraffin that has been cut way from the pipe walls is above the tool and is flushed upwards and out of the well by the flowing oil, without becoming lodged around the tool itself. The smooth surface of the weighted tube, with its decreased diameter, permits it to slide readily through paraffin deposits, and also offers less opportunity for the paraffin to stick to the tool. The bore through the center of the tool permits the continuous flow of oil through the tool, even though it may become lodged in a heavy layer of paraffin, thereby preventing a build-up of pressure below the tool and averting the danger of having the tool blow up the well. In addition, the flow of oil through the hole in the tool emerges just underneath the knife and keeps the knife washed clean of paraffin which has been cut loose.

The cutter 29 preferably has its blade inclined downwardly and outwardly relative to the inner vertical wall of the casing at an acute angle up to 45°. The lower turns of the helix or the spiral of the cutter may be crimped into small narrow folds simultaneously. This crimping breaks up the sliced off sediments into small particles. The following turns of the cutter then easily scrape off the remainder of the sediment left on the wall. In the alternative, a plurality of radial fins running parallel to the axis, such as 33, shown in FIGURE 8, may be used.

The helical or spiral spring steel knife, by virtue of its thin, small surface and of its cutting angle from vertical up to 45°, produces a greater slicing action and comminution than a conventional knife disc with its cutting edge perpendicular to the axis of the pipe. This angle also prevents the knife from becoming lodged in the joints of the pipe. When the sedimentation causes an obstruction, sufficient to extend the distance between sleeve 30 and collar 31, FIGURE 4A, the cutting angle is auto-

matically decreased, allowing it to turn closer to the vertical past any minor obstruction.

The sleeve mounting of the knife permits a certain amount of repeated jarring action. If the knife should encounter paraffin of such hardness that the weight of the tool is unable to pull it through, the weighted part of the tool can be raised repeatedly the distance of the knife-guide rod without disturbing the position of the knife. When the weighted part is then dropped, it imparts a thrust to the knife when the upper stop of the knife guide rod strikes the knife sleeve.

In FIGURE 2 the embodiment of the invention shown in FIGURE 1 is shown, slightly changed.

The central rod 12 is provided with an axial bore 40. The wire 13 is not attached to the top of the central rod, as in FIGURE 1, but passes freely through the bore 40 and connects with a supporting rod 41, of a diameter larger than the bore of rod 12 and having an auxiliary weight 42 attached to its lower end. Weight 42 is axially suspended within a thin walled tube 43 for reciprocation therein. Tube 43 has its upper portion provided with jet orifices 45 directed into the casing around the central rod. The lower end of rod 12 is threaded at 46, FIGURE 8, to engage the threaded upper end of the bore of tube 43, thereby to rigidly unite these parts, as clearly shown upon FIGURE 6. The bottom periphery of the upper portion 44 of the tube forms a stop to the upward movements of the weight 42. The cutter blade 29 is mounted on the central rod 12 in the manner described with reference to FIGURE 1. This arrangement provides for a double jarring action of the cutter blade, if the latter should be retarded or stopped in its progress. Upon being lowered in assembly into the well, the cutter blade proceeds first by its own momentum. If the blade is retarded or stopped by the sedimentation, the weight 42 continues its own downward progress, ceases to support by its upper part the upper portion 44 of the tube 43. Thus the tube itself creates, by its own momentum, a first jarring action upon the cutter blade through socket 14. If the cutter blade does not respond to it by continuing its downward progress, the weight 42, in its own travel through the tube 43, finally hits the bottom of the tube 43, creating a second jarring impact of the socket 14 on the cutter blade.

FIGURE 6 shows details of the means to connect tube 43 with the central rod 12 and the wire 13 with the weight 42.

FIGURE 7A shows a form of the invention wherein knife guide rod 12 has a tube section 30a attached to it. A vane 33 is fixed to and outstands radially from the tube section, and the ends of the blade 29 are secured to the respective ends of this vane, with a full 360° turn about the rod. This construction is also shown upon FIGURE 8.

FIGURE 7B shows another form wherein rod 12 has a sleeve 30b and a collar 31b attached to it, in axially-spaced relation. Vane 32 is fixed at its ends with the sleeve and collar, and blade 29 is, in turn, fixed at its ends to the respective ends of the vane.

Instead of a rope socket, with the knife-guide rod and cutting assembly attached below, shown in FIGURES 1 and 2, FIGURE 8 combines the functions of the rope socket and guide rod by providing a central bore 40 through the guide rod 12 and securing the wire at the lower end of the rod by means such as a doughnut or eyelet 47. This combination permits the positioning of the knife assembly at the extreme upper end of the tool's assembly, eliminating the possibility that dislodged paraffin collecting on obstructions would impede its progress out of the well.

It should be understood, of course, that the foregoing disclosure relates only to preferred embodiments of the invention and that it is intended to cover all changes and modifications of the examples of the invention herein chosen for the purposes of the disclosure, which do not constitute departures from the spirit and scope of the invention set forth in the appended claims.

What is claimed is:

1. In an apparatus for cleaning well casings, a rod, a sleeve mounted on and about said rod at one end thereof for free axial sliding therealong, a collar mounted on and about said rod at the other end thereof for sliding adjustment therealong, a single blade comprising a length of resilient metal fixed at its ends with said collar and sleeve, respectively, and extending helically about said rod for at least 360° thereabout, means operable to fix said collar to said rod in adjusted position therealong, and means fixed with said rod limiting movement of said sleeve therealong in a direction away from said collar.

2. In an apparatus for cleaning well casings and tubing, a rod, a sleeve mounted on and about said rod for limited sliding therealong, a collar mounted on and about said rod, below said sleeve, for adjustment therealong, a single blade of resilient metal strap having its ends secured to said sleeve and collar respectively, and extending helically about said rod for at least one full turn thereabout, means releasably securing said collar to said rod in adjusted position therealong, means limiting upward movement of said sleeve on and along said rod, and a tubular weight having its upper end secured to the lower end of said rod in coaxial relation therewith.

3. In an apparatus as in claim 2, said rod having a diameter less than the external diameter of said tubular weight, the upper end of said tubular weight having by-pass orifices whereby fluid may flow upwardly through said tubular weight, through said orifice, thence upwardly exteriorly about said rod.

4. An apparatus for cleaning well casings and tubing comprising, a tubular rod, a sleeve mounted on and fitting about said rod for axial sliding therealong, abutment means fixed with said rod to limit upward sliding of said sleeve with respect to said rod, a collar mounted on and fitting about said rod, below said sleeve, for axial adjustment therealong, a blade of elongated strip material having its ends fixed with said sleeve and said collar, respectively, a tubular weight fixed with the lower end of said rod in coaxial relation therewith, there being a radial passageway through the wall of said tubular weight at the top end thereof, and means for connecting a cable directly to engage and support said rod.

5. An apparatus as in claim 4, said tubular weight comprising a plurality of like sections detachably connected in fixed coaxial relation.

6. An apparatus for cleaning well casings and tubing, comprising a tubular rod, a sleeve mounted on and coaxially about said rod for translation therealong, first abutment means fixed with said rod to limit upward translation of said sleeve with respect to said rod, a collar mounted on and coaxially about said rod, below said sleeve, for adjustment axially therealong, a blade disposed helically for at least 360° about said rod and having its ends fixed with said sleeve and said collar,

respectively, a tubular weight below said rod, means detachably fixing the upper end of said tubular weight with the lower end of said rod, in coaxial relation therewith, there being passageways at the upper end of said tubular weight through which fluid may flow upwardly and exteriorly about said rod, an auxiliary weight loosely slideable along said tubular weight, second abutment means fixed with respective ends of said tubular weight and determining respective upper and lower limiting positions of said annular weight with respect thereto, and a supporting cable passing downwardly through said tubular rod and having its lower end fixed with said auxiliary weight.

7. The apparatus as recited in claim 6, said sleeve and collar being normally spaced axially of said rod, means operable to fix said collar in adjusted position axially along said rod.

8. An apparatus for cleaning well casings and tubing, comprising, a tubular rod, having upper and lower spaced abutment means, a sleeve mounted coaxially on and about said rod for sliding therealong, a collar mounted coaxially on and about said rod, below said sleeve, for sliding therealong, a blade of strip spring steel having its ends fixed with said sleeve and collar, respectively, and extending helically about said rod, said sleeve and collar having limited sliding movement on said rod between said abutment means, a tubular weight detachably fixed with the lower end of said rod in coaxial relation therewith, there being a passageway through said tubular weight at the upper end thereof through which fluid may flow upwardly through said tubular weight, thence upwardly exteriorly about said rod, an auxiliary weight loosely mounted within said tubular weight for limited movement axially thereof, and a supporting cable extending through said rod and having its end fixed with said auxiliary weight.

9. In a device for cleaning tubing, a rod having a central longitudinal axis, a sleeve mounted on and about said rod for guided translation along said axis, a collar mounted on and about said rod for guided translation along said axis, a cutter blade of resilient metal helically disposed for at least one full turn about said axis and having its ends fixed, respectively, with said sleeve and said collar, abutment means fixed with said rod and limiting axial translation for said sleeve in the direction away from said collar, and means operable to fix said collar in any selected position of axial adjustment along said rod.
